W. H. Field,
Making Cut Nails,
N° 37,340. Patented Jan. 6, 1863.

UNITED STATES PATENT OFFICE.

WILLIAM H. FIELD, OF TAUNTON, MASSACHUSETTS.

IMPROVEMENT IN MACHINES FOR MAKING SHOE-NAILS.

Specification forming part of Letters Patent No. 37,340, dated January 6, 1863.

all whom it may concern:

Be it known that I, WILLIAM H. FIELD, of Taunton, in the county of Bristol and State of Massachusetts, have invented a new and use-

Improvement in Machines for Making Shoe-Nails; and I do hereby declare that the following is a full, clear, and exact description of the same, reference being had to the accompanying drawings, forming a part of this specification, in which—

Figure 1 represents a longitudinal vertical section of my invention taken in the plane indicated by the line xx , Fig. 2. Fig. 2 is a n or top view of the same.

Similar letters of reference in both views indicate corresponding parts.

This invention consists in the arrangement of a furnace, in combination with the cutter of a nail-machine and with the plate from which the nails are to be cut, in such a manner that the plate, while being fed to the machine, passes through the furnace and is presented to the cutter in a red-hot state.

To enable others skilled in the art to make use of my invention, I will proceed to describe its construction and operation with reference to the drawings.

1 represents the cutter, which is inserted into the cutter-head B, being made adjustable in the same by means of set-screws, in usual manner. The cutter-head B is carried in a frame, C, being attached to the frame by pivots or by a shaft passing through the lower extremity of said cutter-head, so that it swings freely backward and forward in a vertical plane. The frame C, which carries the cutter-head, oscillates in a vertical plane on pivots between the lugs a, which project from the upright b of the main frame. The double oscillating motion of the cutter is produced in the following manner: The cutter-head connects by a rod, b', with a crank-shaft, e, to which a rotary motion is imparted by means of a belt or in any other desirable manner. By the action of the crank the cutter-head completes one oscillation for each revolution of the shaft e. The frame C, which carries the cutter-head, connects by a rod, d, to a crank, e, which is secured to the rotating shaft f. This shaft receives motion by means of gear-wheels g h from the driving-shaft c, and it is geared up in such a manner

that it makes one revolution while the driving-shaft makes two, and, furthermore, the motion of the cutter-head is brought in such a relation to the motion of the oscillating frame that the cutter acts whenever the frame has reached its extreme position toward one side or toward the other. The said plate may therefore be fed to the cutter in a rectilinear direction and without a side motion, the angular shape of the pieces cut off being produced entirely by the oscillating motion of the frame C. The crank e, which imparts motion to this frame, is slotted, so that the connecting-rod d can be shifted and the throw of the frame adjusted. The plate, which is indicated in red outlines in the drawings, is fed to the cutter through a tubular channel, D, which passes through the furnace E. The furnace is arranged as close to the cutter as possible, and that portion of said channels which projects beyond the furnace is slotted to admit the projecting hook i of the nippers or tongs F. These nippers are forced toward the cutter by means of a weight, G, which is suspended from a rope or chain, j, and said rope or chain extends over a pulley, k, in the upper end of the upright b, and under a pulley, l, in front of the furnace, and it connects with the hook i by means of a link, m.

The furnace is constructed with a suitable grate and ash-pan, and the feeding-tube extends through it in such a position that the same, with the plate contained therein, becomes well heated.

The operation is as follows: After a fire has been built in the furnace and the furnace-doors have been closed, the said plate is put in the nippers or tongs F and introduced into the feeding-tube D, and the link m is hooked onto the end of the nippers. While passing through the furnace the plate is heated, and the cutting operation can be continued without interruption. By the oscillating motion of the cutter the plate is cut into a number of wedge-shaped pieces suitable for shoe-nails. These nails drop down into a trough or a series of troughs, by which they are conducted to a suitable box or receptacle.

It is obvious that my invention is applicable to nail-machines of different construction, and I do not want to confine myself to the precise construction previously described;

but as far as my experience now goes the furnace is of peculiar value when employed in the manner and combination herein shown.

Having thus fully described my invention, what I claim as new, and desire to secure by Letters Patent, is—

The employment or use of a furnace, E, in combination with the cutter A of a shoe-nail

machine, and with the feeding-tube D, constructed and operating substantially in the manner and for the purpose specified.

WILLIAM H. FIELD.
